UNITED STATES PATENT OFFICE

MAXWELL H. SUSSMAN, OF NEW YORK, N. Y., ASSIGNOR, BY MESNE ASSIGNMENTS, TO
STEEL AND TUBES, INC., A CORPORATION OF OHIO

MACHINE FOR CUTTING BARS, PIPES, ETC.

Application filed October 19, 1926. Serial No. 142,536

My invention relates to machines for cutting bars, pipes and other (usually) lengthy articles, either severing the same into pieces of appropriate length, or making cuts of other kinds, simple or complex, and particularly for performing such operations while the article is traveling. The invention is especially intended for mechanisms for conjoint use with machines in which the articles operated on are formed or otherwise treated, in which connection the desired cuts can be made as the article or articles emerge from the machine treating the article and without interrupting the continuity of the treating operation. It will be apparent, however, that my invention may be used in other situations.

The object of my invention is to improve machines of the kind indicated in various ways, particularly to the end of simplification, eliminating the customary bed plate, eliminating elements customarily devoted solely to guiding the tool carriage, providing a more open construction of the machine, whereby inspection, adjustment and repairs are more readily effected, providing a machine requiring less attention from the operator and in instances dispensing with an operator, the machine delivering the cut pieces automatically without the services of an attendant, and providing a machine suitable for cutting small sizes and also for cutting work of large cross dimensions and consequently so heavy as to be handled manually with difficulty. These and other accomplishments of my invention will appear from the matter hereinafter.

The accompanying drawings illustrate a machine for severing pipe, bars, etc., embodying my invention. Fig. 1 is a diagrammatic elevation of the entire machine, the electrical control circuits also being shown diagrammatically and the tool in its retracted at-rest position. Fig. 2 is a sectional elevation of the delivery mechanism substantially on the line II-II of Fig. 1. Fig. 3 is an elevation partly in section of the portion of the machine of Fig. 1 adjacent the cutting tool, showing this portion in greater detail and the tool at about its position at the com-

pletion of a cut. Fig. 4 is a plan view of the same portion of the mechanism. Fig. 5 is an end elevation of the machine, looking from the left of Figs. 1, 3 and 4, a part being broken away, and the tool retracted. Fig. 6 is an end elevation of the same portion of the machine as Fig. 3, looking from the right of that figure, a part of the mechanism being broken away and the tool depressed.

In the machine illustrated, the work (indicated by the pipe or tube 35) is assumed to be driven longitudinally from left to right in Figs. 1, 3 and 4, by external means; for example, the driving means may be the machine in which the work is fabricated. The cutting portion of the machine illustrated has two end frame members, 1 and 2, which may comprise or have legs resting on the floor and which are transverse to and joined by four bars 5, 5, 6, 6, laid substantially parallel to the direction of movement of the work. These bars lie in two or more planes and together with the frame members 1 and 2 form the framework of the cutting portion of the machine and outline a three-dimension space quite open and accessible. In this open and accessible space much of the mechanism is mounted. The main motive power of the machine is furnished by an electric motor 7 supported by the frame member 1. This motor runs constantly while the machine is in operation and through a small reducing gear 8 on its shaft and chain 9 drives a larger gear at 10 fixed on the shaft 11 extending across the top of the machine. A worm 12 is fixed to this lay shaft 11 and meshes with the gear 13 fixed to the short longitudinal shaft 14 which has a clutch 16 to connect the shaft 14 to a gear 15. The clutch 16 is closed to drive the gear 15 by means of the lever 17 as the latter is actuated by the armature 18 of a solenoid 19, and furthermore, is of the kind which, when once closed by a pull of the armature 18 on the lever 17, remains closed until the gear 15 completes a whole rotation and then automatically opens to disconnect the gear 15. The gear 15 meshes with and drives a gear 25 fixed to the long shaft 26 extending lengthwise of the machine at its top; at its opposite end the long shaft 26 has fixed to it a gear

27 like the gear 25, and these two gears 25 and 27 mesh respectively with gears 28 and 29 which are fixed respectively to the short shafts 30 and 31 carrying the discs 32 and 33. Between the edges of the discs is a long extended bar 34 constituting the wrist or pin of a crank from which the cutting tool is hung as later described. This crank lowers and raises the cutting tool, to and from the work, to make a cut and return the tool each time the clutch 16 is closed and the crank is thereby revolved once by the motor 7 through the connection indicated. In addition to this motion of the tool to and from the work, the tool also moves to the right from its position in Fig. 1 while making a cut, traveling along the crank 34 with the work as later described. It is returned again to the left by the chain belt 48. For driving this belt the end of the worm shaft 11 opposite the gear 10, is provided with a small gear at 39 which drives a chain 40 going to a larger gear at 41 carried by a stub shaft 42, and a gear 43 on this stub shaft meshes with a gear 44 which also meshes with a gear 45 on a shaft 46; this shaft 46 carries a sprocket wheel 47 over which one end of the chain belt 48 passes. The opposite end of the belt passes over and is supported by the sprocket wheel 49. The chain belt is constantly in motion therefore (so long as the main driving motor 7 is running), and will be observed to be laid parallel to the direction of movement of the work, the lower run of the chain moving (right to left) in the opposite direction to the work. A clutch fastens the tool to the lower run of the chain when a cut is completed and thus the tool is returned to its initial left-hand position. This I find is a simple and convenient method of driving a tool parallel to the work.

The bars 5 and 6 are not only parts of the frame of the machine, but I also use the lower pair of bars 5 as guides and supports for the clamp and work-supporting carriage 52. The base plate 52 of the clamp carriage has rolls 55 at its sides running on the two lower bars 5 of the frame, and also similar rollers 56 running against the undersurfaces of the bars 5 so that the clamp carriage is tied to but movable along these bars. On this carriage is a clamp for the work 35 consisting of a lower clamp member 57 fixed to the plate 52 and a movable upper member 58 sliding on guide bars 60 and normally urged upwardly to release position by springs 61. The work 35 is contained within the opposing recesses in the members 57 and 58. To depress the upper member 58 to fasten the clamp and clamp carriage 52 to the work, two eccentric cams 62 are pivoted to the tops of guide bars 60 and provided with arms 63 having slot and pin connections with the tool carriage whereby they are operated by the raising and lowering of the tool carriage. In the depressed position

of the tool carriage and arms 63 (Fig. 6) the cams depress the movable member 58 of the clamp so that the sub-carriage is clamped fast to the work 35, and in the raised position of the tool carriage and arms 63 (Fig. 5) the movable member 58 of the clamp is allowed to rise under the thrust of its springs 61 and release the sub-carriage from the work 35. A member 64 having a bell-shaped entrance directs the work 35 into the clamp.

The tool illustrated is a circular saw 54 on the shaft of a constantly running electric motor 53 which is mounted on the base plate 67 of the tool carriage. In its movement toward and from the work (as crank 34 revolves) the tool carriage is guided by four upright guides 66 rising from the clamp carriage base 52 and co-acting guides 68 on the tool carriage respectively encircling the guides 66. The tool carriage 67 is suspended from the crank 34 by the yoke 69 attached to the base 67, and at its arch hinged to a connecting rod member 70 projecting downwardly from a carriage 71 having an upper roller 72 rolling on top of the extended crank bar 34 and the underneath rollers 73 running on the underside of the crank bar. The pins 78 operating in the slots of the clamp cam arms as before mentioned project from two of the guides 68 of the tool carriage.

The operation of cutting may now be described along with certain details not yet mentioned. The motor 7 is assumed to be running, and also the saw-driving motor 53 and saw 54. Prior to making a cut (the clutch 16 being open) the tool carriage and clamp carriage are at rest at their left-hand positions (Fig. 1), and the work 35 passes freely through the clamp 57-58 from left to right. When the solenoid 19 is energized momentarily, however, the clutch 16 is closed and the crank 34 is caused to go through one rotation as pointed out before. In this rotation the crank first lowers or forces down the tool carriage (the guides 68 sliding on the guide members 66) so as to force the constantly rotating saw through the work 35. Before the tool 54 actually begins to make its cut in the work, however, the arms 63 of the clamp cams are forced down so far by the pins 78 as to attach the clamp carriage to the work 35, so that thereafter and while the cut is being made the clamp carriage is moved along by the work and rolls the tool carriage along the crank 34, acting through the guides 67 and 68. As the tool makes its cut, therefore, it is driven along with the work 35 at exactly the same speed as the work. The (in this instance) severing of the work is completed by the time the crank reaches its lowest position; the throw of the crank is designed to be sufficient for this result. On the second half of the rotation of the crank 34 and the consequent lifting of the tool carriage, the tool is withdrawn from in front of the new end of

the oncoming work 35 and the arms 63 of the clamp cams are then raised again to release the clamp carriage from the work. After the clamp is thus released and as the tool carriage 5 approaches its upper position (but to the right of its position in Fig. 1) the clutch before mentioned comes into operation to attach the carriage to the chain belt 48 to return the carriage to their Fig. 1 position. This 10 clutch of the machine shown is a toothed member 79 arranged to engage its teeth in the lower run of the chain belt 48. This toothed member 79 is movable vertically and horizontally in a slot 81 (Fig. 4) in a bracket 80 extending from the base 67 of the tool carriage and normally is held in an elevated position by a lower spring 82 as shown in Fig. 6; also it is normally held to the right hand end of the slot 81 by a spring 83 carried on a 15 guide rod 84 (Fig. 4). When the tool carriage proper is depressed so far as to close the clamp 57-58 on the work, the toothed member 79 is unable to reach the chain 48. As the tool carriage rises above this point, 20 however, after a cut is made, the toothed member 79 engages in the lower run of the chain and starts the tool and clamp carriages back to the initial position of Fig. 1 as before mentioned. The purpose of the slotted mounting of the toothed member 79 in the slot 81, as described, is two-fold,—first, this construction enables the spring 83 to partly absorb the shock of the sudden engagement 25 of the toothed member 79 with the chain 48, thereby softening the shock on the entire machine as the carriages are started to the left; second, the spring 83 permits a certain overrun in case the tool and clamp carriages reach their left-hand positions (Fig. 1) slightly in 30 advance of the disconnection of the toothed member 79 from the chain thus rendering very close adjustments unnecessary. The spring 82 and vertical movement of the toothed member also have two purposes:—first this arrangement compensates for any 35 raising of the tool carriage so high as (otherwise) to press the member 79 too hard against the chain; second, this arrangement permits the toothed member to be disconnected conveniently from the chain when the carriages 40 reach their at-rest positions. A downwardly facing cam 86 placed to engage the toothed member at the surface 87 serves for this latter purpose. The lower run of the chain 48 45 may be supported by a strip or channel member 85 against the upward thrust of the toothed member 79 under the pressure of spring 82, and the downward facing cam 86 50 may be mounted on this member 85, being so located as to be struck by the toothed member as the carriages approach their initial left-hand position. Spring-pressed bumpers 88 55 are preferably so placed as to be struck and compressed by the carriages as they approach their initial position, thus softening the 60 stopping of the carriages, and by the energy thus stored in the spring or springs of the bumpers, providing means for promptly starting or assisting in the starting of the carriages in the direction of the movement of the work 35 on the subsequent depression of the tool carriage to make another cut. A pivoted latch 89, normally held in latching position by its spring 90, is arranged to engage 65 an abutment 91 on the tool carriage proper to hold the carriages in their initial left-hand position against the thrust of the bumpers 88 and such drag of the work 35 on the guide 64 and clamp 57-58 as there may be. As the crank 34 reaches its uppermost position at 70 the end of a single revolution, it is stopped, of course, by the automatic opening of the clutch 16, and the parts are thus again left in the position illustrated in Fig. 1. Another cycle may be begun now and another 75 piece cut off by again momentarily energizing the solenoid 19 to engage the clutch, whereupon the tool carriage is depressed as before described, and thereby first released from the latch 89 (which is provided with an adjustable abutment 92 to prevent the latch following the carriage down too far), and thereafter both carriages are started in motion in the direction of the work, first by the bumper 88 or conjointly by the bumpers and the 80 engagement of the clamp 57-58. 85

Each piece severed from the work 35 in the manner described leaves the machine through the bell-shaped guide 97 and is removed by a mechanism which automatically delivers the cut-off lengths to an appropriate place. Conveniently this mechanism may be a chain-belt 98 with article carriers 99 to retain the work on the chain, to which may be added a final delivery roller 100. The chain 98 may be of the sprocket type as illustrated, supported by sprocket wheels 102 and 103; the sprocket 102 is carried by a shaft 104 also having fixed to it a second sprocket at 105 driven by a chain 106 105 which, in turn, is driven by a sprocket at 107 fixed to the shaft 108 to which is attached the sprocket 49 driven through the chain 48 as above described. The delivery chain 98 is 110 constantly driven by the motor 7, therefore through the chain 48. The article supports 99 may be metal pieces bent or constructed to provide a bottom and two side walls (see Fig. 2), these being distributed along the chain 98 (see Fig. 1), and the bottom of each 115 being attached to sprocket links. This transfer mechanism is placed opposite the outgoing bell 97, and the upper run of the chain receiving the work from the bell, 120 travels in the same direction as the work. Preferably the piece-removing mechanism begins to exert a removing tendency before the severance is completed, so that the piece 125 cut off is pulled away from the tool immediately it is free from the on-coming work. 130

To this end I arrange for the transfer chain to travel at a somewhat higher speed than the work 35, as by making the sprockets 105 and 107 of proper diameters with respect to each other as will be understood, and I so place the chain with respect to the tool that the portion of the work to be severed lies on the chain before the cut is completed. While the cut is being made therefore the chain 98, moving faster than the work 35, slides beneath this portion of the work and immediately on the completion of the severance, the severed piece is pulled away from the tool. The piece cut off thereupon quickly acquires the speed of the chain which is rather high preferably for another reason also, namely, to thrust each piece onto the receiver stack 111 of severed lengths. Preferably the severed lengths are given a final thrust onto the pile 111 by the driven roller 100 before-mentioned which is placed somewhere near the exit end of the chain 98 so as to receive the work therefrom. To the driven roller 100 may be added an idler roller 101 to press the length of work against the driven drum 100 for traction purposes; the lower roller 100 may be chain driven from the shaft 110 (to which the sprocket 103 is attached) at the same peripheral speed as the chain 98 or faster. As shown in Figures 1 and 2 idler rollers 112 may be used to press the work against the article supports 99 of the transfer chain 98 for traction purposes; these rollers may be mounted on a horizontal bar 113, brackets 114 being provided on the bar 113 and the rollers being hinged to the brackets 114 by pin and slot connections as indicated at 115, so that the rollers 112 rest their weight against the work to press the latter to the supports 99 and also are adapted for work of various sizes. The roller 101 may be similarly mounted.

The machine is electrically controlled as before indicated and the control circuits for this purpose are diagrammatically illustrated in Figure 1; the electrical connections for supplying energy to the motors 7 and 53 are not shown, however, but will be understood. The incoming lines for supplying the energy for the solenoid 19 for the clutch are indicated at 119 and 120. The gauge for measuring the length to be cut off consist of the switch 121 to be struck by each advancing new end of the work 35 and actuated thereby; this controls the supply of energy to the clutch solenoid, and may be mounted on the bar 113 and adjustable therewith in a convenient manner so that pieces of any length can be cut within the capacity of the machine. As illustrated, the switch 121 has a swinging member 122 hinged at 123 to a bracket 124 suspended from the base plate of 121 and reaching downwardly to the path of the work. When no work is present on the transfer 65 98—99 immediately underneath the swinging

member 122, this member hangs substantially straight down and its upper end bears against one end of a sliding piece 125 held by a slot and pin 128 to the base plate and normally drawn downwardly and to the right (in Fig. 70 1) by the spring 126; underneath the right hand and lower end of the sliding member 126 is a projection 127 from the base plate which prevents the sliding member 125 from being turned further than shown in a clockwise direction on its pin 128. The member 125 is permitted to turn in a counter-clockwise direction, however, to a limited extent as hereafter explained. The switch lever 129 is pivoted and provided with a spring 130 to press the lever away from its cooperating contact 132 and press the operating pin 131 of the lever against the upper and left-hand end of the sliding member 125. As the work 35 advances the new end of the on-coming work strikes the swinging member 122 and turns it counter-clockwise; the latter is thereby forced to slide member 125 upwardly and to the left and this pushes the switch lever 129 into engagement with the fixed contact 132. Substantially, or shortly after the engagement is made, the upper end of the swinging member 122, passes underneath the member 125 (assuming the work to be large enough to move the swinging member this far), thus permitting the spring 126 to return member 125 to the position indicated and permitting the spring 130 to disengage lever 129 from fixed contact 132 and return it to the position shown. The parts are again in the positions illustrated in Fig. 1 with the exception that the work 35 now extends underneath the swinging member 122 and the latter is displaced slightly counter-clockwise with its lower end resting on the work and its upper end standing beneath the sliding member 125. As the cut piece travels from underneath the swinging member 122, the latter, by gravity or otherwise, swings back to the vertical position illustrated in the figure before the new end of the on-coming work reaches it so that it is in position to measure the place of the succeeding cut, the return clockwise movement of the member 122 being permitted by the momentary raising of the lower and right-hand end of the member 125 from the projection 127 by the member 122, the member 125 being returned to 127 by the pull of the spring 126 as soon as the swinging member 122 reaches its vertical position indicated. My invention is not limited to this particular type or kind of gauge, however, as will be apparent.

The described momentary closing of the remote-control switch 129—132 energizes the automatic switch solenoid 135 (through the two lines 136 and 137) and this attracts its armature and thereby engages the two switch arms 138 with their respective fixed contacts. This directly connects the clutch 130

solenoid 19 to the lines 119 and 120 and closes the clutch 16 and brings the severing mechanism into action in the manner before described. To assure the solenoid 135 being energized long enough to bring the clutch into action, I use the third switch arm 140, line 141, and switch 142. The switch arm 140 is also engaged with its fixed contact by the movement of the armature of solenoid 135 and thus completes a circuit from the incoming lead 119 through the solenoid 135, lead 141, closed switch 142, switch lever 140 and lead 143 to the main switch and the incoming lead 120, this circuit serving to keep the solenoid 135 energized until switch 142 is opened. This switch (although not so shown) is located beside a rotating part of the clutch 16 which is provided with a pin or cam (not shown) which holds the switch 142 closed while the clutch is disengaged (crank 34 at its upper position) and for a short time after the clutch starts the crank 34 revolving; at other times the switch 142 is held open. As soon as the clutch has been securely closed, therefore, the solenoid 135 is de-energized by the opening of the switch 142 and thereby the solenoid 135 de-energized, the solenoid 19 de-energized, the lever 17 released and clutch 16 can open at the completion of a single rotation and remains open until the solenoids 135 and 19 are energized again. I prefer the holding circuit arrangement (140, 141, 142), since this permits the use at 121 of a switch which need be closed only momentarily, and this is advantageous. One or more manual and normally open switches, 144, may be located about the machine as desired to permit the operator to make cuts at will, for example, to cut off ends or remove bad spots, etc.

The operation of the machine as a whole can be summarized briefly as follows:

The work (of indefinite length) travels to the right in Fig. 1, at a constant or irregular speed, and the pieces are cut off, one after another, as before described, their lengths being measured by the position of the gauge switch 121 on the bar 113. The transfer mechanism 98-99 and 100 moves constantly, as before explained, being driven by the chains 106, 48 and 40. The portion of the on-coming work 35 to be cut off, lies partially on the belt 98 prior to the cut, and, as its end moves, the swinging member 122, the cutting operation is started. Immediately on the completion of the severance the pieces are removed from the tool and thrust onto the stack or receiver at 111, the final outward thrust being given to the piece by the driven roll 100.

It will be understood that while the foregoing describes a machine embodying my invention, my invention is not limited thereto except as appears in the following claims, and that various features of my invention

are applicable to other assemblies than that shown.

I claim:

1. In a cutter, frame members, a plurality of bars joining the frame members and therewith constituting an open framework, a work-supporting carriage resting on some of the bars, a cutting tool, a carriage for supporting the tool, a crank, supported by the framework, for moving the tool-supporting carriage with its cutting tool toward and from the work-supporting carriage, and cooperating guides on said tool-supporting carriage and the work-supporting carriage for guiding the cutting tool in its movement toward and from the work-supporting carriage, the tool-supporting carriage being supported entirely by said crank and the work-supporting carriage. 70

2. The subject matter of claim 1, characterized by the fact that the work-supporting carriage is below the cutting tool and the cutting tool is suspended from the crank. 80

3. In a cutting machine of the kind indicated, a work support, a crank with a long pin above the work support, and a cutting tool suspended from the crank pin, revolution of the crank moving the cutting tool toward and from the work on the work support and the tool being movable along the 90 crank pin while cutting. 95

4. In a cutting machine of the kind indicated, frame members, a plurality of bars joining said frame members and therewith constituting an open frame work for the machine, a work-supporting carriage on and movable with the work along bars of said frame work, a crank supported on said frame work and having its crank pin substantially parallel to the direction of movement of the work-supporting carriage, a cutting tool carriage hung on said crank pin and movable along the crank pin with the work-supporting carriage, cooperating guides on said work-supporting carriage and said tool carriage to guide the tool carriage toward and from the work and to move the tool carriage in the direction of movement of the work, and power driven means to turn the crank to move the cutting tool toward and from the work-supporting carriage. 100

5. In a cutting machine of the kind indicated, frame members, a plurality of bars joining said frame members and therewith constituting an open frame work for the machine, a work-supporting carriage on and movable with the work along substantially horizontal bars of said frame work, a crank supported on said frame work, a cutting tool carriage suspended like a pendulum from the crank substantially above said carriage and movable with and in the direction of movement of the work-supporting carriage, cooperating guides on said work-supporting carriage and said tool carriage to guide the 110

carriage suspended like a pendulum from the crank substantially above said carriage and movable with and in the direction of movement of the work-supporting carriage, cooperating guides on said work-supporting carriage and said tool carriage to guide the 115

- 6 tool carriage toward and from the work and
7 to move the tool carriage in the direction of
8 movement of the work and power driven
9 means, for turning the crank for moving
10 the cutting tool carriage toward and from
11 the work-supporting carriage.

10 6. In a cutting machine of the kind indi-
11 cated, upright frame members, a plurality
12 of substantially horizontal bars joining said
13 frame members and therewith constituting
14 an open framework, a carriage supported on
15 and moveable along a plurality of said bars,
16 a clamp on said carriage to engage the work
17 to fasten the carriage to the work for move-
18 ment therewith, a cutting tool, a crank sup-
19 ported by said framework above said car-
20 riage by which the cutting tool is carried
21 and from which the cutting tool is suspend-
22 ed, and cooperating guiding means for the
23 cutting tool and carriage for guiding the
24 movement of the cutting tool toward and
25 from the carriage and causing the cutting
26 tool to move substantially horizontally along
27 the crank with the carriage.

25 7. In a cutting machine of the kind indi-
26 cated, a plurality of horizontal bars, frame
27 members joining the bars and therewith
28 forming an open frame work for the machine,
29 an elongated crank substantially parallel to
30 the bars, a cutting tool suspended from the
31 crank and movable along the crank, a clamp
32 carriage below the cutting tool riding on
33 some of said horizontal bars, a clamp on
34 said carriage to attach the carriage to the
35 work for movement by and with the work,
36 and co-acting guide means attached to the
37 suspended tool and said carriage to guide the
38 tool as the revolution of the crank lowers
39 the tool to the work in the clamp and raises
40 the tool therefrom.

40 8. The subject matter of claim 7 in com-
41 bination with an endless belt to return the
42 tool and clamp carriage after a cut is made.

42 9. In a cutting machine of the kind indi-
43 cated, a work support, a substantially hori-
44 zontal guide along which said support is
45 movable, a tool carriage, a saw mounted
46 thereon, an electric motor also mounted on
47 said tool carriage to drive said saw, said tool
48 carriage being movable substantially verti-
49 cally with its saw, and coacting substantially
50 vertical guiding surfaces on the work sup-
51 port and the tool carriage to direct the ver-
52 tical movement of the saw.

52 10. In a cutting machine of the kind de-
53 scribed, a clamp member to be clamped to
54 the work and movable substantially hori-
55 zontally therewith, a tool carriage, a saw
56 mounted thereon, an electric motor also
57 mounted on said tool carriage to drive said
58 saw, a crank extending substantially parallel
59 to the direction of movement of the clamp
60 member and attached to the tool carriage to
61 move the same together with its saw sub-
62 stantially vertically as the crank is revolved,

62 11. In a cutting machine, a clamp for the
63 work including a movable member, a car-
64 riage for the cutting tool movable toward
65 and from the work, and a hinged cam bear-
66 ing on said movable member of the clamp,
67 said cam having a slot and pin connection
68 with said carriage through which the cam
69 is actuated as said carriage is moved toward
70 and from the work.

70 12. In a cutting machine of the kind indi-
71 cated, a cutting tool, means for moving the
72 tool with and by the work while cutting, a
73 constantly moving belt, and means to con-
74 nect the cutting tool to the belt to return
75 the cutting tool after the completion of a
76 cut, said means being yielding to soften the
77 shock of starting the cutting tool on its re-
78 turn movement.

78 13. In a cutting machine of the kind indi-
79 cated, a cutting tool movable toward the
80 work for cutting and also movable from its
81 place while cutting, a belt to return the tool
82 in opposition to the last mentioned move-
83 ment, and a clutch to fasten the tool to said
84 returning belt, said clutch being brought into
85 operation by the movement of the cutting
86 tool away from the work after the comple-
87 tion of the cutting.

87 14. In a cutting machine of the kind indi-
88 cated, a cutting tool movable with the work,
89 means to move the tool toward and from the
90 work, a chain to move in a direction opposite
91 the direction of movement of the tool with
92 the work, and a toothed member, to engage
93 the chain, carried with the tool, said toothed
94 member being engaged with the chain by
95 movement of the tool away from the work.

95 15. In a cutting machine of the kind indi-
96 cated, a cutting tool movable with the work,
97 means to move the tool toward and from the
98 work, a chain belt moving in a direction op-
99 posite the direction of movement of the tool
100 along with the work, a toothed member car-
101 ried with the tool to engage the chain, so that
102 the chain can return the tool from its dis-
103 placement with the work, said toothed mem-
104 ber being engaged with the chain by move-
105 ment of the tool away from the work, and
106 means to disengage the toothed member from
107 the belt on the completion of the return.

107 16. The subject matter of claim 14, char-
108 acterized by the fact that the toothed mem-
109 ber is spring-pressed toward the chain.

109 17. In a cutting machine of the kind indi-
110 cated, a cutting tool movable with the work,
111 means to move the tool toward and from the
112 work, a chain to move in a direction oppo-
113 site the direction of movement of the work,
114 a toothed member carried with the tool, said
115

toothed member being engaged with the chain by movement of the tool away from the work and said toothed member being movable, with respect to the tool, both in substantially the direction of movement of the chain and in substantially the direction away from the chain, and spring means pressing the toothed member toward the chain and in substantially the direction opposite the direction of motion of the chain.

18. The subject matter of claim 17, in combination with a cam to move the toothed member away from the chain to disengage said member from the chain at the completion of the return of the tool by the chain.

19. In a cutting machine, a framework constituted by substantially vertical end frames to rest on the machine foundation and three or more horizontally extending members joining said end frames and therewith outlining an open three-dimension space, a carriage resting on and movable along one or more of said horizontally extending members of said framework, a work clamp on said carriage, a power-driven cutting tool substantially within said three-dimension space and movable toward and from work in said clamp and also movable with said carriage, and a crank having its bearings in said end frames and its pin extending substantially horizontally and connected to said tool for moving the cutting tool toward and from the work.

20. In a cutting machine, a framework constituted by substantially vertical end frames to rest on the machine foundation and three or more horizontally extending members joining said end frames and therewith outlining an open three-dimension space, a clamp carriage resting on and movable along one or more of said horizontally extending members of said framework, a work clamp on said carriage, a tool carriage substantially within said three-dimension space and movable toward and from work in said clamp and also movable with the clamp carriage, a circular saw mounted on said tool carriage, an electric motor also mounted on said tool carriage to drive the saw, guides on said clamp carriage cooperating with guides on said tool carriage to direct the saw in its movement toward and from the work and to move the tool carriage along with the clamp carriage, and a crank having its pin extending substantially horizontally and connected to said tool carriage for moving the cutting tool toward and from the work.

21. In a cutting machine, a framework constituted by substantially vertical end frames to rest on the machine foundation and three or more horizontally extending members joining said end frames and therewith outlining an open three-dimension space, a clamp carriage resting on and movable along one or more of said horizontally extending

members of said framework, a clamp for the work on said clamp carriage, a tool carriage substantially within said three-dimension space, above the clamp carriage, and movable toward and from the clamp carriage and also movable with said clamp carriage, cooperating guides on the two carriages to direct the tool carriage in its movement toward and from the work and to move the tool carriage along with the clamp carriage, a power-driven cutting tool mounted on the tool carriage, and a crank having its pin extending substantially horizontally above the tool carriage, the tool carriage being carried by and suspended from the pin of said crank and being movable along said pin.

22. In a cutting machine of the kind described, a tool for severing the work, carriage means therefor, means for moving the carriage with the work while the tool is cutting, an endless belt, moving in substantially the same direction as the work, to receive the work and remove the severed piece, article supports, providing side walls to retain the work on the belt, being incorporated in the chain, and rollers pressing the work to the belt.

In testimony whereof, I have signed this specification.
